UNITED STATES PATENT OFFICE.

JOSEPH ROBINSON, OF NEW YORK, N. Y.

REISSUED

AUTOMATIC TRAIN-PIPE-CONNECTER HEAD.

Application filed April 2, 1921, Serial No. 458,119. Renewed October 22, 1926.

My invention relates to improvements in automatic train pipe connector heads and has among its object to provide a head of this kind in which the forces set up by the fluid pressure carried are so applied to the heads as to cause the minimum tendency to force the heads apart. In the present forms of connector heads, of which the type shown in my United States Patent #1,245,779 for improvement in automatic train pipe couplings is typical, the fluid pressure passing through the ports of the head, and particularly the lowermost port, sets up forces which tend strongly to part the heads. This is due to the fact that the fluid passes through the head on the axis of the buffer spring by which the heads are held together. In my improvement the fluid is passed through the head at an angle of approximately 45 degrees to the axis of the spring by which the heads are held in contact. In this manner the pressure of the fluid is greatly reduced as respects its tendency to part the heads. By my present improvement the fluid pressure tends to move the heads laterally, one with respect to the other, thereby forcing the guiding means of the head into more effectual engagement, whereas with other types of coupling heads the tendency of the fluid pressure is to blow the heads apart, this because the direction of force set up by the fluid pressure is parallel with the direction of force produced by the buffer spring used to maintain the heads in engagement, as aforesaid. Various means of automatic locks have been restorted to to overcome this tendency to separate previous designs of heads, but my improvement is void of the complication incident to these locks and provides a simple and effective means for reliably minimizing the tendency of the fluid pressure to separate mated heads.

My invention exists in the combination, improvements, and construction hereinafter described, pointed out in the appended claims, and illustrated in the accompanying drawings in which

Figure 1 is a side elevation of my improved coupling head, with the hose 22 and the fitting 12 omitted.

Figure 2 is a front elevation of the structure shown in Figure 1.

Figure 3 is a rear view of the structure shown in Figure 1, taken on line 3-3 of Figure 1.

Figure 4 is a plan view of a pair of my improved coupling heads connected, one thereof being shown partly in sections. In this view the hose 22 and the fitting 12 are shown.

Figure 5 is a rear view of the fitting 12 and a portion of the head, taken on line 5-5 of Figure 4.

Referring to the drawing: My improvement is preferably of the pin and funnel type although of course any other suitable means for aligning the heads may be employed. My improvement comprises the forwardly extending tapered guiding prong or pin 6 and the funnel or ring 7. The prong is positioned in advance of the funnel 7 and on the opposite side of the longitudinal axis of the head as shown particularly in Figure 4. The base 8 of the prong and the base 7 or face 9 of the funnel lie preferably in vertical planes substantially at right angles to the longitudinal axis of the stem 10 of the head. A substantially flat vertically extending perforated portion 11 connects the funnel 7 with the prong 6, and extends diagonally across the aforesaid axis and is preferably formed integral with the funnel and the prong. A suitable fitting 12 Figures 4 and 5, provided on diametrically opposite sides with lugs 13 and having formed in its forward end a gasket seat 14 carrying a gasket 15 is mounted in the perforation 16 of the portion 11 with the gasket 15 projecting slightly through the said portion. The fitting is maintained in this position by suitable dogs 17, formed on the rear side of the portion 11 and comprising, in connection with the lugs 13, a bayonet joint for removably maintaining the fitting or conduit 12 in position in the said perforation.

A pair of horizontally extending webs 18 and 19 lie one above and one below the said fitting and extend from the pin 6 to the funnel 7 and are preferably formed integral therewith and with the said portion 11 as aforesaid. A flat stem 10 is connected to or formed integrally with the said webs, or is otherwise suitably connected with the head, and extends rearwardly therefrom on the longitudinal centre line of the head. The stem is perforated at 20, Figure 1, to receive a suitable support for the coupling head such, for instance, as that shown in my co-pending application Serial #441,699 filed February 1st, 1921. At its rear end the stem is provided with a flange or projection

21 adapted to receive the buffer spring of the support used to suspend the head from the car. When mounted in such support the flange 21 serves to limit the extent of 5 forward movement of my improved coupling head. To provide against accidental disconnection of the fitting or conduit 12 from the portion 11 I so mount the fitting in the ordinary train pipe hose 22 that the 10 latter must be twisted one-fourth turn to the right or left in order to permit insertion of the fitting. This sets up stresses in the hose which causes the fitting to return to the normal service position shown in Figures 4 and 5 in which position it is maintained by the torsional resistance of the 15 hose 22.

It will be observed that the perforation 16 in the portion 11 and the fitting or conduit 20 12, extend through the head at an angle to the longitudinal axis thereof. This is in order to reduce the tendency of the fluid pressure in the conduit 12 to force the heads apart, and also to minimize the friction to 25 the flow of air in passing from one car to the other. The angle at which the conduit leads away from the head should be such as to cause it to point directly to the centre of the opening in the train pipe on the car 30 from which the hose 22 leads. A coupling head constructed to my improvement may on account of the aforesaid reduced tendencies to separate the same, be rigidly maintained in engagement with a complementary 35 head by the use of a buffer spring of low resistance, thereby greatly reducing the strains on the bolts which support the automatic connector from the car coupler and improving the service performance as a whole. For 40 these reasons a distinct advance in the art is made by the present improvement.

What I claim is:

1. An automatic train pipe connector head, 45 comprising in combination, a perforated stem connected with the head at one end and having at the other end a flange, a pair of guides positioned one in advance of the other on opposite sides of the longitudinal axis of said stem, the base of each of the 50 guides being disposed in a plane at substantially a right angle to said axis, a perforated portion extending diagonally across said axis and joining said guides, a fluid conduit mounted in said perforation and extending 55 therethrough and suitably locked therein to conduct a fluid diagonally through said head, and a horizontally extending web projecting across said conduit and joining said guides and said stem.

60 2. An automatic train pipe connector head, comprising in combination, a perforated stem connected with the head at one end and having at the other end a flange, a pair of guides of the pin and funnel type positioned 65 with the pin in advance of the funnel and

lying one on either side of the longitudinal axis of said stem, the ~~base~~ of each of the guides being disposed in a plane at substantially a right angle to said axis, a perforated portion extending diagonally across 70 said axis and joining said guides, a fluid conduit removably mounted in the perforation in said portion and extending therethrough, a bayonet joint for maintaining said conduit in the service position, and a 75 pair of horizontally extending webs extending across said conduit at the upper and lower sides thereof and joining said guides and said stem.

3. An automatic train pipe connector head 80 comprising a front guide and a rear guide arranged on opposite sides of the longitudinal axis of the head, one of said guides comprising a pin having its longitudinal axis 85 extending parallel to the longitudinal axis of the head and the other comprising a funnel having its axis extending parallel to the longitudinal axis of the head, means for supporting said head with its longitudinal axis extending at all times in the general direction of the longitudinal axis of the car to which it is applied, said head having a substantially flat portion extending diagonally between said guides, and a conduit arranged behind said front guide and removably connected to said flat portion of the head. 95

4. An automatic train pipe connector head comprising a front guide and a rear guide, the former lying in advance of the latter, 100 said front guide comprising a pin having its longitudinal axis extending substantially parallel to the longitudinal axis of the head, and said rear guide comprising a funnel having its longitudinal axis extending substantially parallel to the longitudinal axis of the head, a substantially flat perforated portion extending diagonally from one of said guides to the other, a conduit positioned behind said front guide and secured in said 110 perforation, said conduit being removable from and insertable in said opening from the rear of the head while said head is coupled to a mating head.

5. An automatic train pipe connector head 115 comprising a pair of guides, the base of one of which lies in advance of the base of the other and the base of each of said guides extending substantially at right angles to the longitudinal axis of the head, a substantially flat perforated portion extending diagonally from the base of one of said guides to the base of the other, means for maintaining said head with its longitudinal axis 120 extending at all times in the same general direction as the longitudinal axis of the car to which the head is applied, a conduit removably connected to said flat portion of the head and extending rearwardly therefrom. 125 130

6. In a train pipe connector, the combination of a head having a projection adapted to receive an opening in a member of a mating head, the meeting faces of said projection and member being in a plane perpendicular to the longitudinal direction of the connector, said first named head also having a member with an opening adapted to receive a projection on a mating head, the 5 meeting faces of said last named member and projection also being in a plane perpendicular to the longitudinal direction of the connector, said first named head having a cylindrical passageway extending there- 10 through obliquely to the longitudinal direction of the connector, and a fluid-carrying conduit mounted in said passageway.
7. In an automatic train pipe connector, the combination of a head having a shank 15 extending rearwardly thereof and also having a projection on one side of the longitudinal axis of said shank and a ring on the other side thereof, said projection having a meeting face extending in a plane perpendicular to the axis of said shank and said ring also having a meeting face also extending perpendicular to the axis of said shank, said head having a portion thereon extending obliquely to the axis of said shank, 20 said portion having an opening therein in line with the axis of said shank, a nipple arranged in said opening obliquely to the axis of the shank, and a gasket carried by said nipple.
8. An automatic train pipe connector head comprising guides arranged on opposite sides of the longitudinal axis of the head, one of said guides comprising a pin having its longitudinal axis extending parallel to 25 the longitudinal axis of the head and the other comprising a funnel having its axis extending parallel to the longitudinal axis of 30
- the head, means for supporting said head with its longitudinal axis extending at all times in the general direction of the longitudinal axis of the car to which it is applied, said head having a substantially flat portion extending diagonally across the longitudinal axis of the head, and a conduit 45 removably mounted in said flat portion of the head and extending rearwardly thereof.
9. An automatic train pipe connector head comprising a pair of guides, the base of each of said guides extending substantially at right angles to the longitudinal axis 50 of the head, a perforated portion extending diagonally between said guides and having a substantially flat face, means for maintaining said head with its longitudinal axis extending at all times in the same general direction as the longitudinal axis of the car to which the head is applied, and a conduit 55 removably mounted in said perforated portion of the head and extending rearwardly therefrom.
10. In an automatic train pipe connector, the combination with a connector head having a projection and a recess disposed on opposite sides thereof for coupling purposes, and having a shank projecting rearwardly 60 adjacent the central portion thereof, said head having a portion forwardly of said shank provided with a face arranged diagonally of the axis of said shank and provided with an opening, a nipple extending 65 through said opening, means for removably securing the nipple to said portion, the forward end of the nipple terminating substantially flush with said face of said portion, whereby the orifice of the nipple extends 70 obliquely to the meeting face of the head.
- In testimony whereof I hereby affix my signature.

JOSEPH ROBINSON.
